CLAIM

The ornamental design for a sandal upper, as shown and described.

DESCRIPTION

FIG. 1 is a perspective view of a sandal upper showing my new design;

FIG. 2 is a top view thereof;

FIG. 3 is a right side view thereof;

FIG. 4 is a front view thereof;

FIG. 5 is a left side view thereof; and,

FIG. 6 is a rear view thereof.

The broken line outlines of the footwear sole illustrate environment and form no part of the claimed design.

1 Claim, 6 Drawing Sheets(56)
